UNITED STATES PATENT OFFICE.

LEWIS CHARLES LAWALL, OF WAYNE TOWNSHIP, WAYNE COUNTY, INDIANA.

PORTABLE VULCANIZING DEVICE.

1,140,381.

Specification of Letters Patent. Patented May 25, 1915.

Application filed April 26, 1914. Serial No. 335,027.

To all whom it may concern:

Be it known that I, LEWIS CHARLES LAWALL, a citizen of the United States, residing in Wayne township, in the county of Wayne, State of Indiana, have invented a new and useful Portable Vulcanizing Device, of which the following is a specification.

The object of my invention is to provide a device for vulcanizing rubber or rubber composition especially for repairing damaged articles such as punctured or cut pneumatic tires, tubes and casings and solid rubber tires. First, to make said repairs without necessitating the removal of the casing from the wheel or the wheel from the vehicle; second, to do said vulcanizing without danger of damaging tire or vehicle by any flam or excessive heat of vulcanizer; third, to provide a vulcanizer that is automatic in the control of the heat; fourth, a vulcanizer that will not produce an excessive amount of smoke when gasolene or other similar fuel is used in it for producing the proper degree of heat; fifth, to make a vulcanizer that can be used for repairing both outer casings and inner tubes, simple and quick in operation yet compact in form, so it can be readily carried in a tool kit and used on the road as well as the garage.

Another object is to produce a vulcanizer that will be strong and durable in construction, positive, efficient and automatic in control of heat, compact and neat in shape and which can be sold at a comparatively low price, and which may be easily and quickly manipulated to produce the requisite results at a minimum expense.

Other objects and specific advantages of my invention will appear from the specification, and the accompanying drawing as the description proceeds, the invention consisting of the novel features and arrangement of parts as hereinafter particularly described and claimed.

I attain these objects by the device illustrated in the accompanying drawings in which—

Figure 1 is a perspective view of the vulcanizer as mounted for use on an outer casing. Fig. 2 is a top plan view showing the swivel clamp fastened to an auto fender or work bench, with the foot plate snapped on; and a patch and inner tube between the foot plate and vulcanizer; as used for repairing inner tubes. Fig. 3 is a detail section on line 3 of Fig. 2 showing the foot of the clamp,

foot plate, tube, the vulcanizer and the clamp screw. Fig. 4 is a perspective view of the vulcanizer. Fig. 5 is another section of the clamp showing in detail the swivel joint and foot. Fig. 6 shows a perspective of the clamp foot plate. Fig. 7 shows a modified form of clamp for use with the vulcanizer when used for inner tubes only. Fig. 8 is a detail view of the slotted back surface of the swivel joint of the clamp.

In detail similar letters and figures refer to similar parts throughout the several views.

A practical embodiment of the invention comprises a heater or vulcanizing member A with curved base, to conform to the curvature of inflated tire casings, with suitable side, top and bottom projections, with upright plates 12, 12', 12''. The central plate 12' is enlarged at the lower end and contains a socket 11 into which fits the rounded point 10 of clamp screw D. The lower end of the vulcanizer is provided with a flange sufficiently high to keep the fuel from being readily spilled or splashed from well 8, which is the fuel container proper. The clamp B is slotted adjacent the foot 2 to receive the wire spring 6 of foot plate C. Clamp B also has a swivel rod 4 as shown in detail in Fig. 5. Through this rod passes pin 13, the outer ends of the pin fitting into slots 14, 14', 15, 15', Figs. 5, 7, and 8. Positioned about the rod in the countersunk recess in the clamp is a coil spring 16 against which fits washer 17 then pin 23 passing through the rod for holding the spring in place.

Fig. 6 shows the construction of the foot plate C. with slotted lugs 18, 18', 19, 19', into which fits spring 6. In making this detachable foot plate the four lugs may all be slotted at the same time to receive the spring wire 6, after which the slots 20, 20' are riveted or hammered smaller to hold said spring wire firmly in place while the lugs 21, 21' are left open to allow the spring snap wire to work freely in said slots when foot 2 of clamp B is snapped underneath said wire and same enters slot 5 of clamp foot, 2, Fig. 5.

Fig. 7 shows a modified form of swivel clamp G with curved stationary foot plate 22, but with swivel joint same as on clamp G Fig. 1.

In practical use in repairing an outer tire casing or tread the vehicle wheel is turned

- to bring the part of the casing to be repaired to a vertical plane. The aperture or slit is wiped clean with a cloth saturated with gasolene, the patch of properly prepared rubber composition and of suitable size to fill the cut or aperture is applied. Member A is then taken up and into its well 8 is poured a measured quantity of gasolene or other similar fuel. The vulcanizer A is then placed over the patch and the foot of screw D is placed into socket 11 while the foot of clamp B is placed on the opposite side of the tire against the rim and the clamp screw sufficiently turned to give a gentle pressure. The liquid is then ignited. The fuel measuring cup supplied with the outfit is of such size as to furnish enough gasolene to fill the well 8 and allow a minimum overflow into the basin above the well. The basin feeds the flame only until the vulcanizer is sufficiently hot, after which it is kept at the right temperature by feeding only from the small opening of the well 8 thereby restricting the flame practically within the confines of the fuel box, without waste and avoiding the annoying and dangerous flaring up of flames and excessive smoking that is encountered in other devices of somewhat similar construction. When the fuel has been consumed the patch will be found vulcanized to the required degree.
- To repair an inner tube, foot plate C is snapped on the foot of clamp B. The swivel rod 4 of the clamp B is clamped to the work bench or auto running board and the clamp B swiveled to the upright position with the foot plate in horizontal position, the inner tube is laid over the foot plate, the punctured part is wiped clean and a suitable patch placed, and the vulcanizer is charged with fuel and placed as mentioned in the foregoing for outer casings; after which the clamp is turned one fourth turn on the swivel rod as shown in Fig. 2 and the fuel

is ignited and left to burn out, which completes the job the same as in the foregoing in regard to vulcanizing casings.

I am aware that prior to my invention portable vulcanizing devices have been made, I therefore do not claim such a combination broadly, but

I claim as new and desire to secure by Letters Patent of the United States.

1. A vulcanizing device comprising a vulcanizing plate, heat transmitting rib-plates attached to the rear side thereof, a flange extending back from the margins of the vulcanizing face plate to form therewith an open receptacle terminating at the bottom in a narrow deep well having a constricted mouth in combination with a wide shallow overflow basin at the mouth of the well; a central pressure swiveling clamp and a foot plate as herein set forth and described.

2. A vulcanizing device having in combination a central pressure clamp with a swiveling joint comprising a clamp bar having a perforation and cross grooves, a swivel rod passing through the perforation, a spring and a locking pin on said rod so constructed as to allow the swivel joint to unlock and allow the clamp to turn from the upright to the horizontal position and again lock and vice versa as herein set forth.

3. A vulcanizer having in combination a liquid fuel heated member, a swiveling clamp having a slot adjacent the foot and a detachable foot plate with wire snap spring fitting the said slot at the foot of the swivel clamp as shown and herein described.

In testimony whereof I have signed my name to the specification in the presence of two subscribing witnesses.

LEWIS CHARLES LAWALL.
